UNITED STATES PATENT OFFICE

JOSEPH W. HEETER, OF EAST BUTLER, PENNSYLVANIA

FRANGIBLE JOINT

Application filed June 27, 1930. Serial No. 464,264.

My invention relates to frangible joints, and more particularly to frangible joints for well casings and the like.

After a well casing has been sunk, it sometimes becomes necessary to remove all or a part of the casing from the ground. In order to remove the upper part of the casing from the lower part after the casing has been sunk, the upper part must be broken away from the lower part. I provide a frangible joint for accomplishing this purpose.

Briefly, my device consists of a pipe coupling made in two separate collars which are intended to form a part of the casing. The outer periphery of the lower collar is provided with a shoulder extending around its end portion. The other collar is provided with a plurality of shoulders around the inner periphery of its end portion, which shoulders are spaced apart to accommodate the shoulder of the other pipe. The second pipe is telescoped over the first pipe so that a lap-butt-jointed pipe coupling is formed.

The ends of the pipe coupling are welded together in such manner that the weld normally holds them together, but when a sufficient force is applied to the end of one of the collars, the weld is broken. Slots or other suitable openings are provided in one of the collars so that when the coupling is pulled apart the abutting shoulders of the end portions slide over one another, permitting the joint to be broken.

A frangible joint is illustrated in the accompanying drawing, in which

Figure 1 is a view in side elevation of a coupling for a well casing; and

Figure 2 is a sectional view of the coupling taken on the line II-II of Figure 1.

Referring to the drawing, the coupling 1 consists of an upper collar 2 and a lower collar 3. The upper collar 2 is threaded at 4 for the purpose of being screwed on to the upper section of the pipe of a well casing, and the lower collar 3 is threaded at 5 so as to be screwed into a lower section of pipe of the well casing.

The lower collar 3 is also provided with a shoulder 6 which extends around its outer

periphery. The shoulder 6 fits into the space 7 formed by shoulders 8 and 9 that are provided within the inner periphery of the upper collar 2. The latter is telescoped over the upper end of the lower collar 3 in such manner that a lap-butt-joint is formed, which provides for a short relative movement between the upper collar 2 and the lower collar 3.

Initially, the collars are welded together at 10 to connect them rigidly together under normal conditions of use. The weld is made sufficiently weak, however, so that it may be broken by the application of sufficient force such as the weight of the pipe above or by a blow on the top of the well casing of which the coupling forms a part.

The lower portion of the upper collar 2 is provided with a plurality of slotted openings 11 for the purpose of permitting the shoulder 8 of the upper collar to expand and slip over the shoulder 6 of the lower collar when sufficient force is applied to the casing, tending to pull the collars apart.

The coupling 1 is assembled in exactly the opposite way, that is, the female collar is forced over or telescoped on the male collar. The openings 11 permit the end of the collar 2 to expand so as to permit the shoulder 8 to slip over the shoulder 6. The next step in the manufacture of the coupling is to spot weld the collars together at points 10. The coupling is then complete and is ready to be used at the proper point in and as part of a well casing.

It is to be noted that a space between the upper end of the lower collar and the upper shoulder of the upper collar is provided for the purpose of permitting a relative movement between the collars after the weld between them has been broken. This insures a complete and satisfactory break of the weld when this is desired.

A sealing ring 12 of lead or the like is disposed adjacent the upper shoulder of the upper collar in this space for sealing the joint when the weld is broken and the collars are jammed together by the weight of the casing above the joint. In this manner, the coupling is made to form a water tight joint.

While I have illustrated and described a certain preferred embodiment of my invention, it is to be understood that it may be otherwise embodied within the spirit of the invention and the scope of the appended claims.

I claim:

1. A frangible coupling for a well casing comprising telescoping tubular members having coacting abutting shoulders and a weld for normally securing said members together, at least one of said members having slots extending axially through the end thereof to permit displacement of one of said shoulders so that the members may be separated.

2. A frangible coupling for the sections of a well casing comprising tubular telescoping members, the interfitting portions of said members having cooperating shoulders thereon tending to limit relative axial movement therecf, one of said members having its end slotted axially to permit deformation of said shoulders and release of said coupling members, and a frangible weld for normally securing said members in extended relation.

In testimony whereof I have hereunto set my hand.

JOSEPH W. HEETER.
